(57) **CLAIM**

The ornamental design for a connector, as shown and
described.

DESCRIPTION

FIG. 1 is a first front, top, and side perspective view of a
connector.

FIG. 2 is a second front, top, and side perspective view
thereof.

FIG. 3 is a first front, bottom, and side perspective view
thereof.

FIG. 4 is a second front, bottom, and side perspective view
thereof.

FIG. 5 is a top view thereof.

FIG. 6 is a front view thereof.

FIG. 7 is a bottom view thereof.

FIG. 8 is a back view thereof.

FIG. 9 is a side view thereof, the opposite side being a mirror
image; and,

FIG. 10 is a cross-sectional view thereof taken along line
10-10 of FIG. 9.

The cross-sectional views illustrate environment of the
connector and source connector which form no part of the
claimed design of the respective embodiments.

1 Claim, 5 Drawing Sheets

Related U.S. Application Data

continuation of application No. 29/429,467, filed on Aug. 10, 2012, now Pat. No. Des. 747,471.
